KEY CONTAINER

Paul S. Hauton, Atlanta, Ga.

Application May 20, 1938, Serial No. 208,998

12 Claims. (Cl. 70—456)

This invention relates to containers and has more particular reference to containers suitable for pocket use and especially adapted for holding a plurality of keys.

5 The object of the invention is to provide a more generally simplified and efficient container having a substantially smooth exterior when closed and which permits the desired key to be quickly and easily located and manipulated.

10 The patent to Slotnick, No. 1,943,844, dated January 16, 1934, shows a construction in which a plurality of keys are pivotally mounted and frictionally held in place between a pair of spaced walls by a plurality of washers with a swinging flat door closing one side of the container and operating a spring member for simultaneously lifting the ends of all of the keys so as to project the key ends to an accessible position from their normally inaccessible position between the side walls. The present invention permits access to a plurality of keys grouped in juxtaposed position from one side of the group and the selection of the desired key from the group without necessarily swinging out the ends of all the keys.

15 While two embodiments of the invention are shown in the drawings accompanying this application and forming part thereof, it is to be understood that such embodiments are merely illustrative of the underlying principles of the invention so as to afford a clear understanding thereof to those skilled in the art and is not intended as limiting the invention to the specific form disclosed therein.

20 In said drawings—

25 Fig. 1 is a side elevation showing the container in closed position.

30 Fig. 2 is a side elevation showing the container in open position.

35 Fig. 3 is a section of Fig. 1 on the line 3—3.

40 Fig. 4 is an end elevation.

45 Fig. 5 is a section of Fig. 1 on the line 5—5.

50 Fig. 6 is a side elevation of another form of the invention with the device shown in closed position.

55 Fig. 7 is a side elevation of the modified device partly open and partly in section.

60 Fig. 8 is a section of Fig. 6 on the line 8—8.

65 Fig. 9 is a top plan view of the modification shown in Fig. 6, and

70 Fig. 10 is a section of Fig. 6 on the line 10—10.

Continuing now by way of a more detailed description and referring more particularly to Figs. 1 to 5, a key container preferably moulded to preferably form a pair of rigid, spaced, parallel side walls, A and B, one of which is cleared away at A' to form a partly arcuate cutaway portion permitting access to one side of the grouped keys as will be more fully described hereinafter. A transverse wall C connecting the upper edges of the side walls A and B forms one side of the key

75 container and limits the keys from swinging clear of the container in one direction. One end of the transverse wall C terminates short of the ends of the parallel side walls, A and B, to permit the keys to be swung in a limited arc so that the key container or holder may depend from a key when it is inserted in and left in a lock as is frequently desirable and necessary, for instance in using the key container with automobile locks. The end of the wall C also affords a stop for temporarily supporting the keys if desired in a lateral position with respect to the longitudinal axis of the container when a key is being selected for insertion in a lock. The keys are pivotally mounted in the container within the spaced side walls on a preferably detachable key pivoting member comprising the screw D and internally threaded sleeve E. This member connects the side walls A and B and is located near one end thereof. The head F of the screw D may be and preferably is countersunk in the wall A and the head G of the sleeve E may be and preferably is countersunk in the wall B. The head G may be and preferably is prevented from turning relatively to the casing walls by dependent lugs G' adapted to engage recesses formed in the wall B. This arrangement for holding the sleeve E relatively stationary to the container wall, obviates the necessity of slotting the head G, and affords a smooth surface for one side of the container. The keys may be secured within the container on the key pivoting member by separating the screw D and the sleeve E and slipping the conventional key opening over the parts of the pivoting member. Once the keys are in position, the sleeve E may be secured in place by the screw D as will be readily understood. The wall C and pivoted arrangement of the keys on the key pivoting member permit the latter to swing in more or less parallel planes in a limited arc. A swinging door or gate H is preferably also moulded to form a recess J and dependent wall K, the gate complementing wall A and closing off its opening A' and the dependent wall K being opposed to wall C. In order to insure proper seating and alignment of the gate H with respect to the side wall so that the container will present a smooth exterior free of projecting parts, the wall A is undercut at L to receive a correspondingly shaped piece or lap M, formed on the end of gate H, and forming a lap joint with the undercut L. A rounded protuberance or latch N is formed in the gate H and is adapted to snap into a correspondingly shaped keeper P when the latter is in closed position. The gate H is mounted to swing on a pin Q located opposite the pivot point of the key group and affords access to the key ends from one side of the group, if the container is held in a horizontal position when the gate is opened. If the keys are loosely mounted on the key piv-

10 15 20 25 30 35 40 45 50 55 60 65 70 75 80 85 90 95 100

oting member, their ends may be swung out freely by turning the plane of the container toward a vertical position. When the key ends are projected from the container, access is afforded to either side of the keys. Since the keys are ordinarily arranged in definite order as related to the gate, the proper key may be selected without visual inspection. The recess J affords a fingerhold for swinging the gate.

10 The foregoing container relates more particularly to a container in which a plurality of keys are mounted on a single pivot. In the form shown in Figs. 6 to 10, the container is more specifically designed to segregate the keys into groups, the gates being so constructed as to be readily identified solely by the feel of the gate, for instance the shape and depth of the panel in the side wall of the gate, thereby permitting the proper selection of a group to be easily made without usual inspection. The construction shown in the last named modification is also preferably moulded to form a pair of spaced walls R and S (R being the front wall and S the back wall), having key pivoting members T and U of a construction similar to the screw D and sleeve E. The members T and U are located at opposite ends of the container. A transverse, diagonal partition or wall V, divides the key container into two key holding compartments, adapted to hold 25 the key ends, in opposite position, the wall R being cut away on opposite sides of the partition V. A gate W, adapted to close the upper cutaway portion is pivoted at X and retains the keys pivoted on U in the upper key compartment of the container and a gate Y pivoted at Z retains the keys pivoted on T in the lower compartment of the container. The gates W and Y are lapped at W' and Y' and register with corresponding undercuts on the cutaway portion of 30 the wall R, for holding the closed gates or doors in proper alignment with respect to the side wall R. Gate W has a latch W'' snapping into a keeper recess R' and gate Y has a latch Y'' snapping into a keeper R'', similar to the latch and keeper arrangement described in connection with Figs. 1 to 5.

In the form shown in Figs. 6 to 10 the swinging doors or gates may and preferably have definite characteristic configurations to enable the user 35 to distinguish the doors by "feel" so as to facilitate determination of the desired key group.

Since the key container is, in its preferred embodiment preferably moulded to the form illustrated, a rigid construction with properly aligned 40 parts is achieved, with comparatively thin material.

I claim:

1. A key container comprising a moulded housing having spaced rigid side walls, a connecting wall formed with the side walls with an opening therebetween, one of the side walls having a cut away portion and a pivoted gate closing the cut away portion and spanning the opening between said rigid side walls the gate swinging in 45 a plane parallel to the housing side.

2. A key container combining spaced side members, means to pivot a plurality of keys between the spaced side members so as to swing freely in planes parallel to the side members, one 50 of the side members being cleared away to permit access to the end of the space normally occupied by the free ends of the keys from one side of the group.

3. A container comprising a housing having spaced side walls with an opening therebetween, one of the walls having a cut away portion and means to close simultaneously the cut away portion and a portion of the said opening. 5

4. A key container comprising means therein for pivoting a plurality of keys said container having spaced walls lying in substantially parallel planes, one of the walls being cut away so as to afford access to the keys from one side of 10 the key group and a swinging gate adapted to close off the cut away portion.

5. A key container comprising a pair of spaced walls, a detachable pin connecting the spaced walls for pivoting a plurality of keys, one of the spaced 15 walls being cleared away at one end thereof so as to permit access to the end of the keys from one side thereof, and a gate pivoted at the opposite end of the container at which the keys are pivoted, to close the cleared away portion of 20 one of the spaced walls.

6. A key container combining a housing comprising a pair of spaced walls, a detachable pin connecting the walls for pivoting a plurality of keys in parallel relationship, means to limit 25 movement of the keys around the pin, one of the spaced walls being cut away and a gate having a flat wall to close the cut away portion and an edging strip to retain the keys in position.

7. A key container comprising a housing having 30 a diagonal partition dividing the container into a pair of tapering key compartments, pivoted doors for each compartment and key retaining flanges on said doors.

8. A key container comprising a housing having 35 a diagonal partition dividing the container into a pair of tapering key compartments, doors for each compartment oppositely pivoted and keeper flanges on said doors.

9. A key container comprising a housing having 40 spaced walls and a diagonal partition between the walls dividing the container into a pair of key compartments, one wall having a cut away portion over each compartment and a door to close each cut away portion, and means to maintain the door in alignment with and latched to the wall. 45

10. A key container comprising spaced walls having grouped keys therebetween, one of the walls having a cut away portion and a pivoted 50 gate to close off the cut away portion, the gate having a dependent wall for closing the space between the side walls to retain the keys in housed position when the gate is closed and to afford access to the side of the keys and to permit the ends of the keys to swing clear of the container when the gate is open. 55

11. A side wall arrangement for key containers comprising a side wall having a cut away portion and an undercut portion, a gate adapted to 60 close off the cut away portion and having a lap to engage the undercut portion and means to hold the gate in closed position.

12. A key container comprising a housing having substantially parallel side walls and means 65 for securing at their head portion a plurality of keys in super-imposed relation between said side walls, one of said side walls being cut away so as to afford access at the bit portion of the keys from one side of the group, and means including a swinging member adapted to close off the 70 cutaway portion.

PAUL S. HAUTON.
